CLAIM

The ornamental design for an andiron, substantially as
shown and described.

DESCRIPTION

FIG. 1 is a top perspective view of an andiron showing
my new design, shown partially in section for clarity of
disclosure.

FIG. 2 is a top plan view thereof.

FIG. 3 is a rear elevational view thereof, with one of the
support legs shown fragmentarily for completeness of
disclosure.

FIG. 4 is a side elevational view, the opposite side being
a mirror image thereof.

FIG. 1

FIG. 4

FIG. 2

FIG. 3
